UNITED STATES PATENT OFFICE.

RICHARD J. McCARTY, OF KANSAS CITY, MISSOURI.

DESIGN FOR A BOLT.

SPECIFICATION forming part of Design No. 35,172, dated October 8, 1901.

Application filed July 25, 1901. Serial No. 69,735. Term of patent 14 years.

To all whom it may concern:

Be it known that I, RICHARD J. McCARTY, a citizen of the United States, and a resident of Kansas City, in the county of Jackson and State of Missouri, have invented and produced a new and original Design for Bolts, of which the following is a full, clear, and exact specification.

My design consists in the novel features of form disclosed in the accompanying drawings, in which—

Figures 1 and 2 represent the new form of bolt as viewed in two directions at right angles to each other, and Figs. 3, 4, and 5 are transverse sections taken, respectively, on the lines 3 3, 4 4, and 5 5 of Figs. 1 and 2.

As shown in the drawings, the leading or material features of my design are a bolt having both its ends threaded and an intermediate offset or enlargement on each of the diametrically opposite sides of the bolt, forming a shoulder, each shoulder tapering to-

ward and extending to one of the threaded ends of the bolt, so that each shoulder grows smaller as it approaches said threaded end, the taper of each shoulder being greater near the face of the shoulder than near the threaded end of the bolt, the face of each shoulder being made so as to conform to whatever surface it may be intended to engage, all portions of the bolt not covered by the shoulders and situated between the threaded ends having their diametrically opposite sides parallel.

Having thus described my invention, what I claim as new, and desire to secure by Letters Patent, is—

The design for a bolt, substantially as herein shown and described.

The foregoing specification signed this 15th day of July, 1901.

RICHARD J. McCARTY.

In presence of—

E. N. INGELS,
H. B. JOHNSON.
